**METHOD AND APPARATUS FOR ROLLING
METAL STRIP AND SHEET**

Louis H. Taylor, Youngstown, Ohio, assignor to The Youngstown Research and Development Company, Youngstown, Ohio, a corporation of Ohio
Continuation-in-part of application Ser. No. 239,199, Nov. 21, 1962. This application May 19, 1965, Ser. No. 457,104

27 Claims. (Cl. 72—21)

ABSTRACT OF THE DISCLOSURE

A method and apparatus for rolling metal sheet in a rolling mill a small diameter work roll and at least one upper and one lower backing roll for the work roll which are driven by separate motors in which deflection of the small work roll is controlled by effecting changes in apportionment of the torque applied by the motors to the driven backing rolls. Means are provided to sense the amount and direction of the deflection of the small work roll which produces a signal related to the amount and direction of the deflection. An error signal is produced related to the difference between the sensed position and the desired position and transmitted to the motors to effect changes in apportionment of the applied torque and thereby control deflection of the work roll and the shape of the issuing strip.

This application is a continuation-in-part of my application Ser. No. 361,418, filed Apr. 21, 1964, now Patent No. 3,275,918, which is a continuation-in-part of my application Ser. No. 239,199, filed Nov. 21, 1962, now abandoned, which is a continuation-in-part of my application Ser. No. 734,321, filed May 9, 1958, now Patent No. 3,077,800.

This invention relates to a method and apparatus for rolling metal strip and sheet, and more particularly to a method and apparatus for maintaining deflection of a small diameter work roll of a roll stand substantially at a given position in the roll pass of the stand. The deflection to which my invention relates is in a direction with and opposite to travel of metal through the mill, and the small work roll is one of a plurality of rolls of a stand, all of whose longitudinal axes are in substantially the same vertical plane.

Generally, this small diameter work roll is on a 5-high stand, a 3-high stand, a 4-high stand, or a 6-high stand where it is the smallest diameter roll of the stand. On the 5-high stand, it has an upper and lower intermediate roll each of larger diameter and an upper and a lower backing roll each of greater diameter than the intermediate rolls and each backing roll in frictional engagement with its intermediate roll. This work roll is in frictional engagement with the one intermediate roll and forms with the other intermediate roll a roll pass through which the metal travels and in which it is reduced in thickness.

On the 3-high mill, the roll is the smallest roll and is disposed between two backing rolls, each of which is driven by an electric motor.

On the 6-high mill, this small diameter work roll forms with a larger diameter work roll the roll pass. The diameter of the larger work roll is substantially about one and one-half to four times the diameter of the small work roll. The two work rolls are interposed between upper and lower intermediate rolls which, in turn, are interposed between upper and lower backing rolls. The upper intermediate roll is in frictional engagement with one of the work rolls and the lower intermediate roll is in frictional engagement with the other work roll while the upper backing and upper intermediate rolls are in frictional engagement as are the lower intermediate and lower backing rolls.

2

The given position of the small work roll in the roll pass can be one at which the longitudinal axis of the small work roll is in vertical alignment with the longitudinal axes of the other rolls of the mill or it can be one at which the small work roll is bowed or deflected in a direction with or opposite to travel of metal through the mill. In this latter case, the longitudinal axis of the small work roll is not in vertical alignment with the longitudinal axes of the other rolls of the mill. Selection of the given position is dependent upon production of a desired shape in the rolled metal which in most cases is flat, and takes into consideration crown in the rolls due to the shape of the roll bodies and/or to heat generated by reduction of the metal. During the course of rolling, the given position may be changed intentionally to obtain a desired shape in the metal or to maintain shape. This change in the given position may be required because of variations in conditions in the roll pass such as heat build-up in the roll body or bodies or because of variations in the metal itself, such as hard spots or off-gauge.

Driving force or torque for the small work results from frictional engagement with at least one backing roll or intermediate roll and from application of forward tension to the metal by a winding reel or another stand on the exit side thereof.

In recent years, there has developed an increasing demand for wide metal strip and sheet, particularly in the very thin gauges such as 0.001" to 0.008" with a special emphasis upon flatness. Although it is recognized that small diameter work rolls readily bite into the metal being rolled, reduce screw pressures and make reductions in gauge of the metal which cannot be made with larger diameter rolls, efforts to use such small diameter rolls, especially those which are too small to be driven through their necks (those with diameters 1" to 4") have been unsuccessful. This has resulted from inability to control the deflection of these rolls in the plane of metal travel through the mill as a consequence of which it has been highly difficult to obtain a specified degree of flatness in the strip or sheet. The uncontrolled deflection or bowing of the small diameter work roll causes over-rolled edges or ripples and/or over-rolled center portions or buckles in the strip. When this occurs in the thin gauges, it is costly and troublesome, if not impossible, to remove the buckles and ripples and off-gauge strip is produced, thereby rendering it unsatisfactory for specifications and orders.

Two factors can cause this deflection, the first being an unbalance of force acting upon the small work roll and the second being a combination of forces generated by the screwdown mechanism of the stand acting upon the top backing roll and of the tolerances in the bearings and chocks for the backing rolls, intermediate rolls and the work roll. Considering first the deflection caused by the unbalance of forces acting upon the rolls, and referring to FIGURE 1 which shows diagrammatically a 5-high mill, that mill comprises a top backing roll 1 and a bottom backing roll 2 with a top intermediate roll 3 and a lower intermediate roll 4 disposed therebetween. The top intermediate roll is in frictional engagement with the top backing roll, and the lower intermediate roll is in frictional engagement with the bottom backing roll with the backing rolls being driven by electric motors, not shown. However, the intermediate rolls can be driven instead of the backing rolls. Disposed between the two intermediate rolls is a small diameter work roll 5 in frictional engagement with the lower intermediate roll 4 and forming a roll pass with the top intermediate roll 3. Extending through the roll pass is metal strip 6.

A combination of two resulting forces rotates the work roll 5. The first resulting force acts on the top side of the

roll and comprises a portion of strip delivery tension T_d and tangential force F_1 generated by the top backing roll 1 acting upon the top intermediate roll 3 and extending transversely through the strip thickness to the top part of the work roll 5. The sum of these two forces tends to move the roll 5 towards the delivery side of the mill as shown by arrow 7.

The second resulting force acts on the lower side of the work roll 5 and comprises a tangential force F_2 produced by rotation of the lower backing roll 2 in frictional engagement with the intermediate roll 4. The other component of this second resulting force is the entry tension T_e which, together with the tangential force F_2 , acts to move the work roll 5 towards the entry side of the mill as shown by arrow 8. Consequently, for equilibrium conditions corresponding to a servo lateral deflection and zero bearing loads on the rolls, the following condition exists: $(T_e + F_2) = (T_d + F_1)$.

The second factor which causes the deflection results from a combination of forces generated by operation of a screwdown mechanism and of tolerances in the roll bearings and chocks. When the screwdown mechanism lowers the top backing roll and the top intermediate roll to establish a given roll pass to effect a particular reduction, the screwdown mechanism exerts a force on the rolls. This force, in combination with the tolerances between the roll necks, the bearings and/or the chocks and tolerances in the mill housing, may cause the work roll to deflect in the direction with or opposite to travel of strip through the mill. Such deflection occurs because of the small amount of space between the bearings and the roll neck and between the chocks and the mill housings, thus enabling the roll necks and/or chocks to shift or move a small amount when subjected to the screwdown force.

Control over deflection of the small work roll to obtain a desired shape or flatness in the strip encounters further complications from a heat build-up in the rolls, especially during sustained rolling periods. This heat build-up cannot be completely dissipated by flood coolant and generally effects an expansion or swelling commonly called "crown" in a center portion of the small roll and/or in any other roll. Presence of the crown causes over-rolling of the center portion of the strip, thereby requiring compensation in the position of the small roll in the roll pass to minimize if not eliminate its effect upon the shape of the strip. Thus, regulation of deflection of the single small roll presents many problems which place severe requirements upon a control system therefor.

Full realization of advantages from use of the single small diameter work roll has been hampered by inability to very quickly effect a correction or compensation for deflection to maintain or return the roll at or to a given position in the roll pass. Since the metal is traveling through the mill at speeds from about 500 f.p.m. to about 6,000 f.p.m., a substantial amount of defectively-shaped strip can result where even a 2-4 second period is consumed in returning the work roll to its given position. Production of defectively-shaped strip is unwanted for it must either be cut out of the coil or the coil diverted to another order, thereby materially increasing costs of manufacture.

My invention permits full utilization of the advantages of the small diameter work roll by maintenance of deflection of the roll at a given position in the roll pass and by ability to effect an extremely fast correction for deviations in deflection from the given position. Specifically, it comprises maintaining the deflection of a small diameter work roll substantially at a given position in the roll pass and/or controlling the amount of deflection of this work roll in the roll pass on a rolling mill which has at least one upper backing and at least one lower backing roll for the work roll. This deflection of the small work roll is in the direction substantially with and substantially opposite to travel of the metal through the mill. Each of the backing rolls has a diameter greater than the

diameter of the small work roll and the rolls are disposed substantially vertically of one another. The work roll and one of the upper and lower backing rolls form a roll pass through which metal is reduced in thickness and another backing roll is in frictional engagement with the work roll. At least one electric motor is operatively connected to an upper backing roll and at least one electric motor is operatively connected to a lower backing roll. Maintenance and/or control of the deflection results from increasing and decreasing the amount of the deflection by effecting changes in apportionment of applied torque by the motors between the driven rolls through sensing amount and direction of deflection of the work roll from the given position. From this sensing, a signal related to the amount of deflection and related to the direction thereof is generated and then from the signal an error signal related to the difference between the sensed position of the work roll and the given position of the work roll and related to the direction of deflection is produced. Thereafter, the error signal is utilized in regulation of output torque of the electric motors for effecting the changes in apportionment of applied torque to the driven rolls to maintain the small work roll substantially at the given position. Preferably, the sensing of deflection of the small work roll includes sensing the rate of change of deflection and the signal is related to the rate of change of deflection. Further, the error signal is related to the rate of change of difference between the sensed position and the given position of the small work roll.

In one embodiment of my invention, a current related to the magnitude of the error signal and related to the direction of the error signal is produced from this error signal and then applied to the electric motors for effecting the changes in apportionment of applied torque to the driven rolls to maintain the small work roll substantially at the given position or to control the amount of deflection of the small work roll. The current which is produced from the error signal is applied preferably to the armatures of the electric motors to effect the changes in apportionment of applied torque, but it can alternatively be applied to the fields of the electric motors to effect the changes in apportionment. One such current which I have employed comprises a first part which is substantially continuous, is related in magnitude to the amount of the deflection and related to the direction of the deflection. This current also has a second part which is pulses of short duration related in magnitude to the amount of the deflection and related to the direction of deflection. The first part is a major portion of the current and requires a longer time interval to effect a change in apportionment of applied torque than the second part.

I prefer to effect these changes in apportionment of applied torque without substantially affecting the amount of total torque delivered to the driven rolls. Such is accomplished by increasing amount of applied torque to one of the driven rolls by increasing output torque of the motor or motors connected thereto, while simultaneously decreasing the amount of applied torque delivered to the other driven roll by decreasing output torque of its motor or motors. In this way, the small work roll is brought back from its deflected position towards the given position. In practice of my method, I can so carry out the sensing of deflection and utilization of the error signal that deflection of the small work roll is maintained within a range of substantially ± 0.0005 " of the given position. A range of deflection of ± 0.005 " and more can be used for some rollings. This range of deflection in which the small work roll is maintained is in part dependent upon the flatness of the strip, the width of the mill and the diameter of the small roll.

My invention also includes a method of rolling the strip in which a mill operator observes the shape of the strip as it issues from the mill and then, based upon his observation, he controls the amount of deflection of the small work roll to produce a desired shape. In controlling

the amount of deflection he increases and/or decreases the amount of deflection of the small work roll through making changes in apportionment of the torque applied by the motors to the driven upper and lower rolls. Such changes in apportionment of the torque comprise increasing or decreasing the amount of output torque of the motor or motors which rotate one driven roll relative to the amount of output torque of the motor or motors which turn the other driven roll through operation of controls for the motors.

While entry and delivery tension upon the metal strip have an affect upon deflection of the small work roll, I effect maintenance of deflection of this small work roll at the given position in the roll pass through control over the torque applied to the driven rolls of the mill and not through regulation of amounts of tension in the strip. From the standpoint of mill operation, it is preferable to independently regulate amounts of tension in the strip and not attempt to control deflection of the small work roll by changing amounts of tension applied to the metal strip. This is particularly true in rolling the very thin strip, some of which has low yield strengths, wherein it is important to closely maintain amounts of tension within allowable unit stress and thereby avoid strip breakage.

My invention in apparatus for maintaining deflection of the small diameter work roll substantially at a given position in the roll pass comprises a means for sensing amount and direction of the deflection with this sensing means disposed opposite a face of the roll so that deflection is toward and away therefrom. Connected to the sensing means is a signal generating means which produces from the deflection a signal related to the amount of deflection and related to direction of the deflection. Connected to the signal generating means is an error signal generating means which produces from the signal an error signal related to the difference between a sensed position of the small work roll and the given position of this small work roll, and is related to the direction of the deflection. An error signal transmitting means is joined to the error signal generating means and connected to one of the electric motors which are drivingly connected to rolls of the mill and of means coupled to the electric motors for regulating output torque of these motors to effect changes in apportionment of applied torque to the driven rolls to maintain the small work roll substantially at the given position.

Preferably, the signal generating means is such that the signal is also related to rate of change of deflection of the small work roll and the error signal generating means is such that the error signal is also related to rate of change of deflection of this small work roll.

In one embodiment of the apparatus, the error signal generating means is connected to a current producing means and utilizes the error signal to generate a current related to the magnitude of the error signal and related to its direction. This current is then transmitted to the electric motors for regulating their operation to control output torque and thereby effect the changes in apportionment of applied torque to the driven rolls. This current is applied, preferably, to the armatures of the electric motors, but can also be applied to the fields of these electric motors.

The means coupled to the electric motors for regulating their output torque includes a controllable variable load producing device which regulates output torque of the electric motors, is connected to the error signal generating means, and is responsive to the error signal for effecting the changes in apportionment of applied torque. Examples of the controllable variable load producing device include electrically operated friction brakes which are disposed in engagement with the output shaft of the electric motors and which include an eddy current absorption dynamometer with a D.C. excitation winding regulated by the error signal or a current produced therefrom in push-pull manner with no resultant mill speed change

or with a non-overlapping individual load control; generators which are coupled to the motors, whose output is dissipated as heat through load resistors and whose field is regulated the same as the above dynamometer; generators which are coupled to the electric motors from which power is recovered, and whose fields are controlled the same as the above dynamometer; and hydraulic load devices which work upon the output shafts of the electric motors. All of these devices are responsive to the error signal for effecting the changes in apportionment of the applied torque.

The small work rolls to which my invention is especially directed may have diameters ranging from about $\frac{3}{4}$ " to about 8".

10 In the accompanying drawings, I have shown preferred embodiments of my invention, in which:

FIGURE 21 is a schematic diagram of a drive for a rolling mill with changes in apportionment of applied torque to the driven rolls of the mill effected through electrically operated friction brakes connected to driven spindles which are joined to the driven rolls.

Referring to FIGURES 2, 9 and 10, the 5-high mill of FIGURE 1 mounts apparatus 9 for detecting deflection of the single small diameter work roll 5 in a roll pass formed by the upper intermediate roll 3 and the small diameter roll itself. As shown, the lower backing roll 2 is driven by two motors 10 and 11 connected in tandem with motor 10 being shown in FIGURE 2, and the top backing roll is driven by two motors 12 and 13 connected in tandem. The upper intermediate roll 3 is in frictional engagement with the upper backing roll 1 and the lower intermediate roll 4 is in frictional engagement with the lower backing roll 2. Although I have shown the roll drive connected to the backing rolls, it may alternatively be joined to the intermediate rolls, one of which also functions as a backing roll for the work roll 5.

Connected to the sensing apparatus 9 is a signal generator 14 which produces from deflection of the roll 5 a signal related in magnitude and related to direction of the deflection. This signal travels to a push-pull output amplifier 15 (FIGURE 9) where a first portion continues to a push-pull driver amplifier 16 whose output is delivered to a slow acting regulating system 17 (FIGURE 10) and a second portion advances to a bias and trigger generator combination 19 whose output is transmitted to a fast action regulating system 19. The slow regulating system produces a reversible push-pull substantially continuous current and the fast regulating system generates reversible push-pull pulses of current of short duration. These two currents are fed to a buck-boost generator 20 whose output is applied to the armatures of the motors for driving the backing rolls 1 and 2. By boosting the armature current of one roll drive motor combination and bucking the armature current of the other roll drive motor combination, I effect a change in apportionment of torque applied to the driven rolls 1 and 2 to maintain the roll 5 at or return it to a given position in the roll pass.

Considering the sensing apparatus of FIGURE 2, nozzles 21 and 21a connected to conduits 22 and 22a leading from a source of fluid under pressure such as air or liquid straddle both sides of the roll 5, are substantially opposite the face 24 of the roll 5, and are substantially in alignment with the center line of the roll and substantially midway between the ends of the face 24 thereof so that deflection of the roll 5 in the direction with or opposite to strip travel through the roll pass is toward one nozzle and simultaneously away from the other nozzle. Safety bars 25 and 25a mount and position the nozzles opposite the roll face.

These nozzles are located close to the roll face across gaps 26 and 26a between the ends of the nozzles and the roll face so that deflection of the roll 5 produces a change in pressure of the fluid under pressure in the conduits. Preferably, the length of the gaps between the nozzle and the roll face is from about 0.005" to about 0.050" when the roll and its intermediate and backing rolls are in axial alignment as shown in FIGURE 1.

Within the range of deflection of the roll 5, impingement of two jets of air or fluid against the roll face produces back pressure in the conduits 22 and 22a with this back pressure being less when the roll is deflected away from one nozzle to lengthen the gap and greater when the deflection is toward the nozzle to shorten the gap. When the rolls 5, 1, 2, 3 and 4 are in axial alignment, impingement of the two jets against the roll face produces equal amounts of back pressure in the conduits 22 and 22a. The back pressure affects the pressure of air or fluid forming the jet and as the gap shortens, the back pressure increases and as the gap lengthens, it decreases. Accordingly, as the work roll 5 deflects toward the nozzle 26, back pressure in the conduit 22 increases, thereby reducing the strength of the jet from the nozzle 26 and increasing pressure in the conduit 22. Simultaneously, the roll 5 deflects away from the nozzle 26a and decreases back pressure in conduit 22a accompanied by an increase in pressure of the jet from the nozzle 26a and a decrease

in pressure in the conduit 22a. This change in strengths of the jets and the changes in pressures in the conduits are used for detection of roll deflection and the magnitude of the changes are related to the amount of deflection and the direction of change dependent upon an increase or decrease in pressure.

To convert changes in fluid pressure in the conduits into a signal for controlling operation of the mill, the conduits are connected to a signal generator 14 comprising a transducer 27 and a linear variable differential transformer (LVDT) 28 whose output is transmitted to an amplifier 29. The operation of this transducer 27 and the linear variable differential transformer is described in my Patent No. 3,077,800.

FIGURES 3 and 4 show two other types of roll deflection sensing devices which utilize electromagnetic induction to induce eddy currents in the surface of the roll 5 where high frequencies such as 50 kilocycles and higher are used, or to effect changes in the inductive reactance in one or two electromagnetic inductors which changes correspond to shortening and lengthening of gaps between the inductors and the roll face. As shown in FIGURE 3, I locate two electromagnetic inductors 45 and 46, one on each side of the small roll 5 and connect each inductor into a bridge circuit 46a in which each inductor forms one arm of the reactance bridge. The other two arms of the bridge are resistors 45a and 45b of selected values. The two corners of the bridge formed by the junctions of the two resistors and the two inductors are connected to a high frequency source 47a of alternating current as provided by the driver oscillator 75. The other two corners of the bridge formed by the junctions of resistor 45a and inductor 45 and of resistor 45b and inductor 46 are the outputs of the reactance bridge and are connected to the amplifier 29. The reactance bridge circuit has a null balance RC network comprising a variable capacitor 45c and a variable resistor 45d connected in parallel and across one input corner 45e and one output corner 45f.

As to each inductor, changes in reactance as a result of roll deflection are non-linear. However, the two in combination, when disposed in the reactance bridge circuitry, will produce a substantially linear output as a function of roll deflection.

Each inductor is spaced apart from the roll 5 to provide small gaps 48 and 49 between the roll face and the leading face of each inductor, and each inductor generates magnetic lines of flux which travel from the inductor across the gaps to the roll face. It has been found that a gap between the roll face and the leading face of the inductor of about 0.005" to about 0.025" effects satisfactory detection of roll deflection.

For practical purposes, it is better to move the roll against one inductor and null-balance the bridge. The output voltage of the bridge will then be a function of the roll displacement away from that coil and will rise to a maximum value when the roll is against the opposite coil. At a midway gap point, the output voltage will then be substantially one-half of its maximum value which is conducive to good detection and regulating techniques as it can now be matched against an equal reference voltage. Any deviation from this reference is detected by a difference amplifier 78 (FIGURE 9) which can now be further fed into the proper functional circuitry of a regulating system to restore balance.

The single inductor 51a of FIGURE 4 operates similarly to those of FIGURE 3 except that its output is non-linear and it requires additional compensation circuitry for the non-linearity output. In this regard, a reactance bridge circuit 51b, similar to circuit 46a, would have a variable inductance for one arm and a proper valued resistor associated with the variable inductance as another arm. The other half of the bridge comprises the inductor 51a and the resistor 45b.

The roll deflection sensing devices of FIGURES 3 and 4 are described more fully in my Patent No. 3,077,800.

FIGURES 5 and 6 show two additional devices for detection of roll deflection which use changes in reluctance of the magnetic circuit which bridges one or two small gaps to detect the deflection. As shown in FIGURE 5, two transformers 54 and 55 are located on each side of the single small diameter roll 5 and the primary winding of each transformer is connected to a source of A.C. power 47, as provided by an oscillator such as oscillator 75 of FIGURE 9. Transformer 54 has a primary winding 56 and a secondary winding 57 and transformer 55 has a primary winding 58 and a secondary winding 59. Each transformer is spaced apart from the work roll 5 to form the small gaps 60 and 61 between the roll face and each transformer and each primary winding directs magnetic flux linkages to the roll 5 across the gaps and to its secondary winding. It has been found that a gap between the roll face and the transformer of about 0.005" to about 0.025" effects satisfactory detection of roll deflection. The two primary windings are connected series aiding and the two secondary windings are connected in series bucking.

Connected to the two secondary windings 57 and 59 is an amplifier 50 so that output voltage of the two secondary coils travels thereto for production of a signal.

Because the two secondary windings are connected series bucking, the two output voltages in the secondary circuit are opposite in phase and the net output of the two transformers is the difference between the two output voltages.

This net output voltage is related in amount to the magnitude of the deflection and is directional in accordance with the direction of deflection. An amplifier 50 generates from this net output voltage a signal which is related to the amount of deflection and which has characteristics of direction of deflection.

FIGURE 6 shows a single transformer 62 positioned on one side of the single small diameter work roll 5 for detection of roll deflection. In using the single transformer, its voltage output to the amplifier 50 when there is no deflection of the roll and the roll is in the given position in the roll pass is matched with a standard voltage in the amplifier. When there is roll deflection towards or away from the transformer, there is a resulting increase or decrease in the voltage output of the transformer, thereby causing the amplifier to generate a signal of the same character as the signal produced when using two transformers.

FIGURE 7 shows another device for detection of roll deflection which comprises a tube 63 for delivering a fluid such as oil against the face of the roll 5 from a source of oil entering the tube through a flexible pipe 64. A nozzle 65 of the tube is opposite the face of the roll 5 and separated therefrom by a film of oil. The pressure of the oil issuing from the nozzle 65 in combination with the pressure of a spring 69a, to be described hereinafter, may be such that the nozzle backs away from the roll 0.0001" to about 0.001". Accordingly, the nozzle rides this film of oil and avoids a metal-to-metal contact with the roll to eliminate marking the roll face. The rear end 66 of the tube 63 engages an upper portion 67 of a pivoted arm 68 maintained in its neutral position corresponding to zero deflection of the roll from its given position in the roll pass by a spring actuated plunger 69 in contact with an upper portion of the arm. The lower end 70 of the arm 68 engages one end of a rod 71 which carries a magnetic core (not shown) corresponding to core 39. This core is disposed in a linear variable differential transformer 28a identical to the transformer 28. Consequently, deflection of the roll toward and away from the nozzle 65 operates the linear variable transformer 28a in the same manner as transformer 28 to detect deflection of the roll.

A bar 72 extending substantially parallel to the longitudinal axis of the roll 5 carries the tube 63. Opposite the

bar 72 on the other side of the roll 5 is a second bar 73 parallel thereto and having on its side opposite the other face of the roll 5 a cushion 74 made from a material which does not mark or mar the surface of the roll 5 should it contact same in deflection. This other bar assists to maintain the roll 5 within a given range of deflection so that should there be excessive deflection, the small roll will not break or fracture.

The roll deflection sensing devices disclosed herein have ability to detect very small amounts of roll reflection such as 0.0001" from which a signal is produced for maintenance of the roll substantially at a given position in the roll pass. Additionally, these devices are such that use of a flood coolant on the mill does not affect their operation or reduce their ability to detect small amount of deflection.

Referring to FIGURE 9, the linear variable differential transformer 28 has connected thereto an oscillator 75 which supplies A.C. power of high frequency therefor. The signal output of this linear variable differential transformer advances to an amplifier 29 where it is amplified and forwarded to a phase detector 76. This detector rectifies the A.C. roll position signal to provide a D.C. voltage related to the displacement of the roll from its given position in the roll pass with a polarity indicating the direction of the displacement.

A roll position selector 77a produces an adjustable reference D.C. voltage so that a position at which the roll is maintained can be selected by a mill operator. This reference D.C. voltage along with the output of the phase detector 76 is fed to a difference amplifier 78 which provides an output voltage or error signal related to the difference between the actual roll position and the desired position chosen on the selector 77a. The output voltage signal from the amplifier 78 is related in magnitude to the amount of deflection and is related to the direction of deflection.

The push-pull output amplifier 15 receives the output D.C. voltage signal from the difference amplifier 78 and provides sufficient power to drive two separate push-pull circuits which deliver portions of the output voltage signal of the amplifier 78 to the fast acting regulation system 19 (FIGURE 10) and the slow acting regulation system 17. A first portion of the output of this push-pull amplifier 15 is transmitted to one separate push-pull circuit 79 comprising a rate generator 80 and an attenuator 81 connected in parallel with a frequency compensation network 82 and a second attenuator 83. This first portion, like the output voltage signal of the amplifier 78, has a magnitude related to the amount of deflection and is related to the direction of deflection. The rate generator 80 is a differentiating circuit that gives an output signal related to the velocity of the deflection.

The frequency compensation network 82 controls the higher frequency phase of the circuit and amplitude response of feedback circuits to be described hereinafter.

The attenuators 81 and 83 control the gain of a feedback loop and the amount of dampening.

The output of this parallel circuitry advances to an adder 84 which combines the roll position error signal of the compensation network 82 and the rate signal of the rate generator 80 in the proper phases to produce an output error signal. This signal is fed to the slow regulation system 17 through the push-pull driver amplifier 16, which is in circuit with two control fields 85 and 86 of a rotating amplifier 87 (FIGURE 10), such as Amplitidyne, Rototrol, Regulex regulators.

A second portion of the output of the push-pull amplifier is transmitted to a second separate push-pull circuit 88 identical to that circuit 79 comprising the rate generator 80, frequency compensation network 82, the two attenuators 81 and 83 and the adder 84. From the circuit 88, the resulting output error signal is transmitted to the bias and trigger generator 18 connected to thyra-

trons which are a part of the fast acting regulating system 19.

The reference voltage produced by the roll position selector 77 is carefully regulated so that it does not fluctuate with line voltage, load or temperature changes. This reference voltage is derived from a calibrated roll position setting potentiometer located on the mill and convenient for the operator to select a given position. This reference voltage is then used to preselect the performance level required of the regulated quantity which is a current difference corresponding to torque differentials in the mill motor armatures.

Maintenance of the small roll in the given position requires that overall performance of the regulating system consisting of the fast and slow systems prevent over- or undershooting which can bring about oscillations of various frequencies in the roll. In this regard, various time constants of various elements of the mill, both electrical and mechanical, which add up to an overall time constant, must be taken into consideration and each individual time constant reckoned with in designing the regulating system to prevent oscillation.

It has been found that time constants in the various components of the electrical system can be varied within reason by changes in L/R ratios of each circuit. In this connection, the L/R ratio can be shortened by increasing R through addition of external resistors which, of course, effect power losses and require an increase in size or capacity of components in the circuits.

The given position referred to in this application includes a small band of movement such as plus-minus 0.0005", and on wide mills, may be plus minus 0.005". Within this small band of movement, I achieve regulation of deflection of the roll so that the deflection does not exceed on either side of a given line substantially parallel to the longitudinal axis of the rolls, the ranges set forth.

In order to achieve very fast and careful regulation of deflection of the roll, it is mandatory that the upper and lower driven mill rolls have separate motors to permit effecting a change in apportionment of the torque applied by the motors to the driven rolls, and preferably effecting the change in apportionment of the torque between the two roll drives without affecting the total amount of torque imparted to the rolls themselves. It is further preferable that the change in apportionment be made without affecting the main generator's current output. The foregoing roll drive, in combination with my dual regulating system, achieves correction for roll deflection in intervals such as 4 to 17 or 20 milliseconds.

Referring to FIGURE 10, a main generator 89, driven by an A.C. motor 90, is connected to the mill motors 10, 11, 12 and 13 with mill motors 12 and 13 driving the top backing roll 1 and connected in parallel, and mill motors 10 and 11 driving the lower backing roll 2 and connected in parallel. Mill motor 10 is in series electrically with mill motor 12, as is mill motor 11 in series electrically with mill motor 13, and motors 11 and 12 are connected to one side of the generator 89 and motors 10 and 13 are connected to the other side of this generator.

Connected across natural neutral points 91 and 92 on line 93 in the mill motors' power circuits is the buck-boost generator 20 driven by its A.C. motor 94.

The buck-boost generator has a main field 95 connected to the Amplidyne regulator 87 of the slow acting regulation system 17, and a fast field 96 is in circuit with the fast acting regulating system 19. The fast field is a relatively few-turn coil of heavy wire for current input from two back-to-back connected bridge rectifiers 97 and 98 so that the output from the bridges is transformed to field flux which adds to or subtracts from the flux of the main field 95. On the other hand, the main field 95 is a relatively high impedance winding having more turns per coil of small size wire.

Since the buck-boost generator experiences rapid changes in field flux, its field frame is preferably a laminated construction of good grade electrical sheet for fast response and low hysteresis and eddy current losses.

Through addition to or subtraction from the field flux 5 of the main field 95 and the fast field 96 of the buck-boost generator 20 by operation of the fast and slow systems 17 and 19, I produce a steep rise or fall in induced voltage of the armature 99 of the generator 20 and provide a corresponding steep rise or fall buck-boost output 10 armature current. Accordingly, the armature current of the generator 20 flows in either direction in line 93, as indicated by arrows 100 and 101 (FIGURE 10) and increases the armature current in the upper roll drive motors in direction 100, while simultaneously decreasing 15 armature current in the lower roll drive motors. This effects a change in the apportionment of torque delivered by the two roll drives and thereby moves the small work roll towards the given position or maintains same thereat. Of course, flow of the armature current of the booster in the direction of arrows 101 has the opposite effect as to increasing armature current in the bottom roll drive and decreasing it in the top roll drive. Thus, the total amount 20 of torque imparted to the driven rolls remain substantially the same but the amount of torque delivered to one driven roll relative to the other driven roll is affected whereby correction for deflection and maintenance of the roll substantially at the given position is achieved.

Forcing the fields 95 and 96 of the buck-boost generator 20 with higher than normal field supply voltage from the slow acting regulation system 17 and the fast acting regulation system 19 produces a fast response from the generator 20. Additionally, an external resistor 102 in series with the generator armature 99 reduces the time 25 constant of the regulated power circuit, including the mill motors 10, 11, 12 and 13 by reducing the L/R ratio. However, use of this resistor is not essential.

Considering the slow acting regulation system 17, the Amplidyne regulator 87 is driven by the A.C. motor 94a and has the two matched high impedance control fields 40 85 and 86 connected to the driver amplifier 16. One field's connection is reversed as to the other so that when each receives an equal amount of D.C. output voltage from the amplifier 16, the resultant magnetic field flux is zero for one cancels the other.

The driver amplifier 16 (FIGURE 9) includes circuits 45 which affect its time-rate output such as gain, rate feedback, bias and adjustable time constants, and additionally, has two output push-pull circuits which receive the push-pull signal from the adder 84. When the push-pull signal is received by the driver amplifier 16, one output voltage is raised an amount equal to that the other output voltage is lowered. Which output circuit has its voltage raised is dependent upon the direction of deflection of the roll 5, and the amount of raise and of reduction 50 is dependent upon the amount of deflection of the roll.

Application of this D.C. output voltage from the driver 55 amplifier causes one control field 85 or 86 to drive to a higher excitation level, while the other control field is driven to a lower excitation level to effect a net ampere turn current in one direction or the other to induce a voltage in the armature of the Amplidyne. Arrows 103 and 104 indicate the direction of voltage induced in the armature 105 of the Amplidyne 87 by control fields 85 and 86. Accordingly, the armature 105 of the Amplidyne 60 delivers a variable and directional excitation current to the main field 95 of the buck-boost generator 20 which current must have reversible polarity to effect maintenance of the roll 5 in the given position.

A negative feedback for the armature 105 of the Amplidyne 65 comprises a differential field 106 connected across the armature 105 and a network of back-to-back connected zener diodes 107 and 108. This negative feedback 70 improves transient performance and stability of the Am-

plidyne and reduces its residual voltage. Additionally, it serves as a voltage limiter for the output of the Amplidyne by shorting out a trimmer resistor 109 in the differential field circuit of the Amplidyne regulator 87 through the back-to-back connected zener diodes selected for a proper cut-off voltage.

A positive feedback circuit 110 couples the output voltage of the booster generator 20 to the Amplidyne through a field 111 which is adjusted to hold the Amplidyne output and, in turn, the buck-boost generator's output voltage at any level up or down to which level the control fields have pushed the Amplidyne upon receipt of the error signal. Additionally, the positive feedback circuit maintains the booster voltage at that level with a zero signal so that it performs substantially the same function as a servo-motor driven potentiometer. Thus, if an error signal is present, the slow system 17 is quickly driven to adjust operation of the roll drive motors to correct the error and the slow system is held at that correction level of operation so that no further operation of the Amplidyne occurs until receipt of a new error signal. If this were not the case, then a continuous signal would be required for operation of the Amplidyne.

In actual operation of the mill, receipt of error signals occurs at a rapid rate whereby a small level of output plus-minus from the driver amplifier 16 is generally present as the roll deviates from the given position in either direction.

Referring to the fast reaction regulating system 19, it comprises two pairs of back-to-back or cross-connected thyatron tubes 112 and 113 and 114 and 115 with the output of thyatrons 112 and 113 fed to the primary winding 116 of a first transformer 117 and the output of tubes 114 and 115 fed to the primary winding 118 of a second transformer 119. Joined to the grids 120 of each thyatron tube is the trigger generator 121, and to the cathodes thereof the bias 122 of the combination 18 whereby upon receipt of a signal from the trigger generator, one of the two pairs of thyatrons is fired with the direction of deflection of the roll determining which pair.

The trigger generator includes adjustment circuits such as a proportional control and a rate control which singly or in combination effect firing of the thyatron and the conduction angle, thereby directly affecting output inasmuch as once a thyatron tube is fired, it conducts only during the remainder of the half-cycle A.C. wave. The output of the thyatron is dependent upon a time-degree relationship of triggering or firing and generally, output is less than a 180° conduction angle.

The secondary 123 of the first transformer 117 delivers its output to the first full wave bridge rectifier 97 and the secondary 124 of the second transformer 119 delivers its output to the second full wave bridge rectifier 98 connected together on the negative side with the first bridge rectifier. The positive terminals of the two bridges are joined to the fast field 96 of the buck-boost generator 20 and to even value loading resistors 125 and 126 disposed in series with an electrical connection 127 between the common negative line 128 and a midtap 129 between the two resistors.

As long as the push-pull signal from the trigger generator is present, the pair of thyatrons fired thereby are conducting and thereby energizing their transformer for the duration of the signal. The A.C. output of the transformer is converted to D.C. power by the bridge of its pair of thyatrons and this D.C. power is delivered to the fast field 96 of the buck-boost generator 20 where it is transformed to magnetic energy with a steep rise which adds to or subtracts from the main field flux of the generator and thus affects the output of the generator in a steep rise or fall pattern.

The output of the two full-wave bridge rectifiers 97 and 98 is push-pull and is reversible in that if bridge 97 is energized, current flows therefrom through field 96,

then through resistor 126, back to the negative side of the bridge. At the same time, the bridge also self-loads through resistor 125 and the common connection 127. The output of the other bridge is the same except that the current through the fast field is reversed so that this fast field undergoes a magnetic polarity change with each change in firing of one of the pairs of thyatrons.

Where both thyatrons are overlapped on conduction, then at one instant and at some value depending on the degree of overlap, both bridges will have exactly the same voltage output in which event the load current drops to zero for there are no potential differences thereacross. At this point, the bridges will both self-load through their respective resistors 125 and 126.

The slow system 17 performs the major portion of the work for maintaining the roll at the given position and for returning the roll to the given position when it has moved away therefrom through delivery of a substantially continuous current. The amount of output current supplied by the slow system is dependent upon such factors as the difference between the amount of exit and entry tensions and the magnitude of the roll pressures' angular component which can be substantial especially when rolling thin gauges and which tends to force the roll 5 out of the given position, and also upon an unbalance in forces imposed upon the roll which unbalance requires compensation or correction by substantially steady or continuous output current. This slow system cannot satisfactorily effect all the regulation required because of its long time constant which may range up to about 20 seconds.

Transient conditions in the strip such as a sudden change in gauge, a hardness area in the strip, etc., if not very quickly compensated for by the fast regulating system, will quickly offset the small roll and then there is an unreasonably long time consumed to return it to a given position. During this time, a substantial amount of malshaped or defective strip results so that it is necessary to superimpose upon the slow system the fast system to take care of the transient conditions and to dampen the slow system as to oscillatory tendencies so that the gain of the slow system can be made higher than is possible without the fast system.

The two systems act independently and jointly to effect correction or compensation for maintenance of the roll at its given position. For example, when the buck-boost generator is driven towards a rising voltage left to right, viewing FIGURE 10, to add to the top roll drive torque and bridge 97 is fired, it will be an addition to the buck-boost output from the slow field. In the event bridge 98 is fired due to a slight overcorrection of bridge 97, the slow system cannot change the buck-boost generator armature polarity fast enough, but the output from the booster armature is reduced and overcorrection is avoided.

When the roll 5 deflects out of its given position, one bridge is cut off and the other bridge continually conducts until the slow system catches up and forces the roll back to the given position. When a transient condition occurs, the fast system operates very quickly in the order of 4-20 milliseconds to maintain the roll in substantially the given position.

FIGURE 11 shows a modification of the embodiment of FIGURE 10, wherein the fast field 96 of the buck-boost generator is omitted and the resistors 125 and 126 connected to the bridges 97 and 98 are in series with the generator armature 99 and in the neutral circuit 93. In operation of this modification, where bridge 98 aids the generator 20 from left to right, it self-loads through resistor 126 while bridge 97 subtracts from the generator's output through increased voltage drop in loading resistor 125 which is a part of the generator's output circuit from 91 to 92.

In this modification, the thyatrons 112, 113, 114 and 115 are connected in the same way and operated in the

same manner as described regarding the embodiments of FIGURE 10. The bridge diodes of the bridges 97 and 98 must be of sufficient size or rating to conduct the entire generator's output current plus their self-loading current.

FIGURE 12 shows a modification of the embodiment of FIGURE 10 wherein a 3-wire generator 130, such as a Dobrowolsky machine, replaces the buck-boost generator 20. This generator has a main field 131 connected to the Amplidyne regulator 87 which has the same fields as those of the embodiment of FIGURE 10, an armature 132 connected into the neutral line 93 between the motors 10 and 12 and 11 and 13 (not shown) of FIGURE 10, and two derived external neutral points 133 and 134 into which the output of the thyatron 112, 113, 114 and 115 (not shown) of FIGURE 10 is fed through the back-to-back connected bridges 97 and 98. These neutral points are formed from A.C. outputs of the armature winding tapped at one-pole pitch intervals and brought to slip rings provided in addition to the normal commutators which are the D.C. output terminals of the machine.

As shown, two pairs of coils 135 and 136 and 135a and 136a of high reactance and low resistance are connected across two pairs of slip rings 137 and 138 and 139 and 140, and are disposed upon cores 141 and 142, respectively. The voltage between slip rings 137 and 138 and 139 and 140 is alternating and a small A.C. current is always present in the reactance coils 135, 136, 135a and 136a when the bridges are not conducting. The mid-point of each reactance coil is tapped to form the neutral points 133 and 134 and the D.C. output of the bridges is fed into its coil where it divides at the midtap so that one-half of the total current flows in each direction around the core which has no resulting D.C. magnetization.

The two derived external neutral points 133 and 134 provide introduction of the current pulses from the bridges 97 and 98 into the armature circuit of the generator 130. This effects direct introduction of the current pulses into the armature circuit of the generator 130 and thereby eliminates a fast field in the generator 130 and, consequently, avoids interaction between the fast and main fields of the generator 130.

The main field 131 functions the same as the main field 95 of the buck-boost generator 20.

FIGURE 13 shows electric circuitry which provides reversible D.C. pulses of the fast system 19 at a $\frac{1}{4}$ -cycle from a commercial frequency, 3-phase A.C. power source. In this circuitry, a 3-wire, 3-phase A.C. power source 143 is converted to a 2-phase, 4-wire output in the transformer 144. The outputs of the isolated 2-phase side of the transformer 144 are isolated independent 1-phase voltages with 90° phase angle which are fed to the bridge transformers 117 and 119 of the bridges 97 and 98 by gang operated, individual ring core autotransformers 145 and 146 with sliding contacts.

In this arrangement, the bridges 97 and 98 supply $\frac{1}{4}$ -cycle D.C. push-pull pulses from 3-phase, 60-cycle power which on a 60-cycle per second basis is $4\frac{1}{2}$ million seconds. These short pulses result from firing one thyatron only in each bridge for $\frac{1}{2}$ -cycle on the A.C. wave with the two firings overlapping each other by 90° to effect the $\frac{1}{4}$ -cycle D.C. output.

FIGURE 14 shows a fast regulating system which uses two silicon controlled rectifiers 147 and 148, commonly referred to as SCR's, in combination with solid state silicon rectifier devices in place of the two pairs of thyatrons.

As shown, SCR's 147 and 148 are connected across two corners of full-wave bridges 149 and 150, respectively, comprising silicon diodes which have adequate peak reverse voltage rating for the input A.C. supply voltage. Each full-wave bridge applies a full-wave rectified voltage to its SCR which will either absorb the voltage or apply it to the primary winding of the transformer

in circuit therewith as determined by the phasing of the gate or triggering circuit, similar to the thyatron's triggering. Thus, one SCR will do the work of two thyatrons as it can be gated, fired or triggered every $\frac{1}{2}$ cycle on the A.C. wave.

Where each roll drive has a single motor instead of two motors, the armatures of the two motors are connected in series across the main generator 89 with the series connection between the two motors forming one natural neutral point. To this arrangement, I provide a balancer set comprising two motors series connected across the main generator and free to rotate without a mechanical load joined thereto. The series connection between the two balancers provides the other neutral point of a neutral line similar to that of FIGURE 10, so that the buck-boost generator and the fast acting and slow acting systems are similarly employed to effect correction and compensation for movement of the roll out of its given position.

One modification of my invention uses two roll drive motors connected in parallel across the main generator with a buck-boost generator in series connection through its armature with each mill motor. One buck-boost generator aids its motor, while the other opposes its motor since the outputs of the two buck-boost generators are opposite in direction. The fast regulating system feeds the fast field of the two boosters connected in series therewith while the slow system feeds the main fields of the two boosters also connected in series therewith.

FIGURE 15 shows a single mill motor 160 for driving the upper backing roll 1 and a second single mill motor 161 for driving the lower backing roll 2. These two motors 160 and 161 are connected in parallel across the main generator 89 with a first buck-boost generator 162 in series connection with the motor 160 through its armature 163, and with a second buck-boost generator 164 in series connection with the motor 161 through its armature 165. This series connection of the buck-boost generators with their motors is such that the output voltages of the two buck-boost generators are opposite in direction. Thus, one buck-boost generator aids its motor while the other buck-boost generator opposes its motor. Accordingly, the motor being aided takes a larger share of the main generator output current, while the other motor takes a lesser share of this output current. Consequently, a change in apportionment of torque to the driven rolls is effected to maintain or return the roll 5 at or to its given position.

An A.C. motor 166 has a connection with both buck-boost generators 162 and 164.

The buck-boost generators 162 and 164 have main fields 167 and 168, respectively, which are joined to the armature 105 of the Amplidyne 87 in series. For one direction of Amplidyne output, arrows 169 and 170 indicate the direction of voltage induced in the armatures 163 and 165 of the buck-boost generators 162 and 164. For the other direction of Amplidyne output, arrows 171 and 172 indicate the direction of voltage induced in the armatures 163 and 165.

Resistors 173 and 174 in series with motors 160 and 161 and the armatures of the buck-boost generators 162 and 164, respectively, are useful to reduce the regulating current demand on the fast system 19.

Output of the fast regulating system 19 of FIGURE 15 is through an armature 175 of a buck generator 176 in series connection with resistors 125 and 126 in push-pull relation with the two bridges 97 and 98. The armature 175 and the resistors 125 and 126 are in circuit 177 which extends between neutral points 178 and 179 of the motors and buck-boost generators' circuits.

As shown, the buck generator 176 is driven by an A.C. motor 180, but it may be driven by the A.C. motor 166 joined to the buck-boost generators 162 and 164. Voltage for the field 181 of the buck generator 176 with parallel trimmer resistor 181a of the field 181 is supplied by the

Amplidyne regulator 87. The fields 167, 168 of the buck-boost generators 162 and 164 and the field 181 of the buck generator 176 are connected in series.

The field parameter of the buck generator 176 is adjusted by its parallel trimmer resistor 181a so that its armature voltage matches and follows the voltage of the two buck-boost generators 162 and 164 which is across the neutral points 178 and 179 in either direction as determined by polarity reversal set by the slow system 17.

The armature polarity of the buck generator 176 is opposite to that across the neutral points 178 and 179 in either direction so that the bridges 97 and 98 have zero voltage across their output connection points, namely, from point 182 to point 179 in the circuit 177.

In addition to the thyratrons and SCR's, ignitrons produce satisfactory results when connected in the same way as the thyratrons.

A substitute for the Amplidyne regulator is a static type regulator such as magnetic amplifiers with rectified D.C. outputs and silicon controlled rectifiers in combination with silicon diodes to provide a full-wave rectified D.C. output. These are arranged in push-pull circuitry with loading resistors to produce reversible output polarity or are used singly with two electrically isolated main fields of the buck-boost generator.

FIGURE 16 shows a further embodiment of a slow and fast regulating system applied to a four-motor mill drive with a pair of tandem-arranged motors operatively connected to each driven roll. This system has natural neutral points 91 and 92, electrically connected by line 93, and the motor armatures connected into two circuit series pairs to provide a constantly variable and directional armature shunting of the pairs of the motors without affecting output of the generator for a given reduction. Accordingly, current division is affected and thereby output torques of the pairs of the motors to effect changes in amounts of output torque of the top and bottom roll drives in response to the error signal. Such changes are made quickly and free from overshooting and hunting.

This FIGURE 16 system uses the same main generator 89 and motors 10-13 arranged and connected as in the system of FIGURE 10, and has a rotating booster 190 driven by an A.C. motor 191 and connected into the line 93 between the neutral points 91 and 92. The booster 190 is a low residual voltage machine with two 100% ampere turn shunt fields 192 and 193 connected in push-pull relationship to the driver amplifier 16 and forms the slow portion 194 of the system.

The fast portion 195 of the FIGURE 16 system employs silicon controlled rectifiers 196 and 197 (SCRs) to energize one of the bridge rectifiers 198 or 199, depending upon the direction and magnitude of the error signal, through operation of rectifier transformers 200 and 201 interposed between the SCRs 196 and 197 and the bridges 198 and 199. The D.C. output voltage of the bridge rectifiers 198 and 199 is delivered to the line 93 and added to or subtracted from the output of the booster 190 to effect very fast changes in apportionment of output torque from the motors 10-13.

The SCRs receive the error signal through gate pulse generators 202a and 202b, one of which is operable dependent upon the direction and magnitude of the error signal. The bridge rectifiers comprise silicon rectifier diodes 203.

Connected across the booster is a voltage divider resistor 204 which in combination with blocking diodes 205, 206, 207, and 208, unblocks the bridge rectifiers when bucking the current in the neutral line 93. The blocking diodes 205-208 prevent shorting out of the end portions c or d of the voltage divider 204 regardless of the booster's polarity, and provide a conducting path for that rectifier bridge (198 or 199) which is operated by the error signal to buck the current in line 93 as maintained by the booster 190, or as suddenly raised by operation of one of the rectifier bridges 198 or 199.

The voltage from the rectifier bridges 198 and 199 is added to the voltage of the booster 190, and, therefore, instantly is available. However, this is not the case when one rectifier bridge 198 or 199 is required to suddenly block the current in line 93, for this bridge is actually blocked by a voltage drop which takes place across resistors 209 or 210 which are in circuit with the armature of the booster 190. End portions of the voltage divider 204 across the booster are so adjusted that the voltage at c is the same at the anode or negative end of the bridge 198 as the voltage at its cathode or positive end as at neutral point 91. This voltage then is the drop in the resistor 209 plus the drop in the armature of the booster 190. In effect, there is a small current such as 1-5 amperes through the rectifier bridge 198 when the transformer 200 is not energized. The other end portion d of the voltage divider 204 is likewise so adjusted that the same conditions take place on bridge 199.

As shown in FIGURE 16, the fast system includes A.C. switching bridges 211 and 212, each with an SCR, but a pair of back-to-back connected or inverse parallel SCRs can be substituted for each A.C. switching bridge. For control over the deflection of the small work roll, the firing circuitry of the SCRs is arranged for phase-retarding controlled firing on the half-cycle wave, i.e., to retard or advance the firing. Thus, in the case of a large error signal, full conduction or fully advanced firing of the SCR is required; while for a small or diminishing error signal, less conduction is needed and the firing is retarded.

The two resistors 209 and 210 are required to by-pass the two bridge rectifiers because of the reversing polarity needs of both the fast and slow portions of the control current in line 93. These resistors 209 and 210 are helpful in reducing the time constant of the circuitry; however, they do this at the expense of increased power demand.

A further embodiment of my invention comprises substitution of a balancer set for the two motors 11 and 13 of the system of FIGURE 16, wherein the balancer set 40 is two electrically rotating machines, such as a pair of electric motors smaller than the motors 11 and 13 and drivingly connected to each other. In this embodiment, a modified FIGURE 16 system, motor 10 drives the bottom roll and motor 12 drives the top roll. The pair of smaller electric motors, the balancer set, are disposed and connected as motors 11 and 13 of the FIGURE 16 system, except that the output shafts of these smaller motors are connected to each other instead of to the top and bottom roll drives. This balancer set performs substantially the same functions electrically as the motors 11 and 13 in the FIGURE 16 system, and permits a single motor to drive the top driven roll and a single motor to drive the bottom driven roll.

FIGURE 17 shows a regulating system for effecting the changes in apportionment of applied torque. This system lacks a slow portion and uses back-to-back connected SCRs 213 and 214 which are in rectifier bridges 219 and 220, respectively, to form an adjustable voltage, reversing polarity regulator 215 connected by line 93 between the neutral points 91 and 92 of the same four D.C. mill motors 10-13 operated by the generator 89 shown in FIGURE 16. The back-to-back connected SCRs 213 and 214 are joined to a common line 216 which forms one output terminal of the regulator 215 whose other output terminal is the center tap 217 of a coupling resistor 218. One-half of this coupling resistor 218 is in the neutral circuit and serves a dual role: first, to improve the response of the system by decreasing the time constant, L/R ratio, of the regulated circuit; and, second, to connect the free D.C. output ends of the two rectifier bridges 219 and 220 and these serve as a surge protector or limiter. These two rectifier bridges 219 and 220 have a common 3-phase input 221 and are protected against surge A.C. currents by an air core reactor 222 in each phase.

Firing of the SCRs of one or the other of the two rectifier bridges 219 and 220 is effected through that gate pulse generator 223 or 224 which receives the error signal, and, of course, which particular rectifier bridge is fired is dependent upon the direction of the error signal. As shown in FIGURE 18, this error signal is received by the gate pulse generators 223 and 224 from the adder 84. Depending upon which direction the deflection of the small work roll is to be changed by effecting change in apportionment of applied torque, the system of FIGURE 17 generates a current in the neutral circuit which increases output torque of either the two motors connected to the top driven roll or the two motors connected to the bottom roll, while simultaneously decreasing the output torque of the other pair of motors the same amount without affecting the output of the generator 89. To produce the increase and decrease of output torque of the motors 10-13, the system of FIGURE 17 very quickly produces a current which affects operation of these motors to bring about the changes in apportionment of applied torque to the driven rolls.

The system of FIGURE 17 also operates satisfactorily through a common source of single-phase A.C. power input of proper voltage commensurate with D.C. output voltage.

FIGURE 19 shows a regulating system which has two independent full-wave rectifier bridges 225 and 226 which receive the error signal through bias and gate pulse generators 227 and 228. The rectifier bridge 225 has in circuit a field 229 of a motor 230 which drives a top roll (not the small work roll) of the mill. Likewise, the rectifier bridge 226 has in circuit a field 231 of a motor 232 which drives a lower roll (not the small work roll) of the mill. Each bridge includes two SCRs 233 and 234 connected to its gate pulse generator and two silicon diodes 235 and 236 and receives single-phase A.C. input. SCR 233 and SCR 234 of each bridge are alternatively triggered on the conducting half cycle to provide a D.C. output current, and the diodes 235 and 236 of each rectifier bridge are always in the alternate conductive state, one on each half cycle.

The output of the system of FIGURE 19 is a current resulting from the error signal and having a magnitude related to that of the error signal and related to the direction of the error signal. This current is supplied to the fields of the two motors 230 and 232. The gate pulse generators are so arranged that upon receipt of an error signal, one of the two bridges is phase advanced, while the other is phase retarded upon its SCR firing. Accordingly, one field of one motor has its excitation increased, while the field of the other motor has its field excitation decreased in substantially equal amounts with the resulting armature counter-voltage change effecting the required change in motor output torque to produce the changes in apportionment of applied torque to the driven rolls.

At a zero error signal both motor fields are at the same and at some level as set by a bias value which corresponds to a field rheostat setting. Such biasing causes both gate pulse generators 227 and 228 to fire the SCRs at the same phase angle and thereby effect equal output.

In addition to the regulating systems of FIGURES 17 and 19, another system which lacks fast and slow portions and which achieves satisfactory results uses a rotating booster (preferably a fast response one) with double forcing fields such as the booster 190 of FIGURE 16. This system is similar to the slow portion of the fast and slow systems described herein and has the components of FIGURE 18 in the arrangement thereof except that a first control amplifier is substituted for the gate pulse generator and amplifier unit 223 and a second control amplifier replaces the gate pulse generator and amplifier unit 224. The output of this first control amplifier is sent to one push-pull field (such as field 192 of the booster generator 190 of FIGURE 16 connected

across the neutral points of a 4-motor drive circuit), through a SCR field driver and the output of the second control amplifier is sent to a second push-pull field (such as field 193 of the booster generator 190) through another SCR field driver.

FIGURE 8 shows application of my invention to a 2-stand tandem 5-high mill 151 on which the strip 6 travels from an unwind reel 152 to a first stand 153 where it advances between the upper intermediate roll 154 and the small diameter work roll 155. From the first stand, the strip then proceeds to the second stand 156 where it enters a roll pass formed by the lower intermediate roll 157 and the small diameter work roll 155 and then on to the winding reel 158. Such rolling practice presents both sides of the strip to a small diameter work roll so that each side receives a major portion of reduction in one roll pass, and so that where the rolls are tungsten carbide, both sides of the strip have superior surface from the standpoint of smoothness, brightness and finish. This is important where the strip is to be plated or where plate or strip requires a high, shiny finish.

Examples of 5-high mills on which my invention is useful include one mill with a 1" diameter small work roll, two 3" diameter intermediate rolls, and two 15" diameter backing rolls, and a second mill has one 3½" diameter work roll, two 12" diameter intermediate rolls and two 40-42" diameter backing rolls.

As shown in FIGURE 20, my invention is applicable to a 6-high mill 237 which comprises a small diameter work roll 238 and a large diameter work roll 239, an upper intermediate roll 240 and a lower intermediate roll 241, an upper backing roll 242 and a lower backing roll 243. All of the rolls are arranged so that they lie in substantially vertical alignment, and the upper intermediate roll is in frictional engagement with the large work roll and the upper backing roll is in frictional engagement with the upper intermediate roll. Correspondingly, the lower intermediate roll is in frictional engagement with the small work roll and the lower backing roll is in frictional engagement with the lower intermediate roll.

The metal strip travels from an entry or pay-off reel 244 between the small and large work rolls which form the roll pass of the mill to a winding reel 245. In operation of this 6-high mill, it is the small work roll 238 whose deflection is maintained at a given position in the roll pass by sensing deflection thereof and then effecting changes in apportionment of torque applied to the driven intermediate rolls as described herein, to keep the small diameter work roll substantially at the given position in the roll pass. Drive for the mill is by a pair of tandem joined motors 248 through a spindle 246 connected to the upper intermediate roll 240 and by a pair of similarly arranged motors 249 through spindle 247 connected to the lower intermediate roll 242.

The large work roll 239 has a diameter substantially one and one-half to four times and preferably four times the diameter of the small work roll, and thereby such a greater resistance to deflection that its deflection is not a matter of concern.

This 6-high mill has significant advantages which include:

(a) Ability to drive the intermediate rolls rather than the large backing rolls and thereby obtain higher rotational speeds and smaller drive components of high speed and less torque, together with improvements in over all time constants.

(b) Ability to impart a proper contour or crown to the intermediate rolls for a particular kind and width of strip, thereby leaving the other rolls with a straight or uniform body shape. This is desirable for carbide work rolls where only a minimum amount of metal should be removed per grind.

(c) Both driven rolls thrust radially in the same direction due to the torque reaction and the work rolls also

thrust in the same but opposite direction to the driven intermediate rolls. Likewise, both backing rolls encounter radial thrust in the same direction so that there is no pressure or separating cross-over force in the mill to contribute to a cross-bow or mudguard shape in the strip.

(d) Ability to effectively lubricate and cool the lower roll assembly which includes the small work roll, lower intermediate roll and lower backing roll.

(e) Use of tungsten carbide work rolls, the larger of which has a diameter such that it is not subject to objectionable roll deflection; for example, 3" diameter and 7½" diameter tungsten carbide work rolls whose ability to make reductions is that of two steel rolls less than 4" in diameter for the same separating force.

FIGURE 21 shows a first motor 250 drivingly connected to an upper intermediate roll (not shown) of a 6-high mill through shaft 251, and a second motor 252 drivingly connected to a lower intermediate roll (not shown) of the mill through shaft 253. Mounted in engagement with shaft 251 is a first eddy current absorption dynamometer 254 with a D.C. excitation winding, and mounted in engagement with shaft 252 is a second similar dynamometer 255. Each of the dynamometers applies a variable load upon its shaft and thereby regulates output torque of the motors 250 and 252, and each is responsive to the error signal whose magnitude and direction are dependent upon amount and direction of deflection of the small diameter work roll. Each dynamometer is operated to preload each shaft a given amount so that there is an additional load on each motor.

One error signal which satisfactorily operates the dynamometers 254 and 255 is that produced by the system of FIGURE 19 and is converted to a current which operates the dynamometer 254 from bridge rectifier 225 and which operates the dynamometer 255 from bridge rectifier 226. In operation, the error signal and the current therefrom, acting through one dynamometer, effects an increased load upon one shaft and, acting upon the other dynamometer, effects a decreased load upon the other shaft to effect the changes in apportionment of applied torque to the driven rolls. This increased and decreased load applied to the two shafts tends to drop or momentarily drops the angular velocity of the heavier-loaded shaft, and tends to raise or momentarily raises the angular velocity of the lighter-loaded shaft, and thereby produces the changes in torque to maintain the small roll at the given position in the roll pass.

Regarding the hydraulic load devices, one example comprises two hydraulic pumps, one coupled to the drive shaft 251 of FIGURE 21 and the other coupled to the drive shaft 253 with the motor 250 operating the one pump and motor 252 operating the other pump. Each pump forces a hydraulic fluid through its closed self-loading piping loop which includes a control valve for regulating volume and pressure of the fluid traversing the loop through control over the size of a passageway through the valve. Each of the two valves for the two loops can be operated by the system of FIGURE 19 and is responsive to the error signal from bridge rectifiers 225 and 226 respectively, similarly to dynamometers 254 and 255.

Heat generated in the fluid during operation of the pumps is dissipated by a heat exchanger connected into the loops.

Where loads on the pumps are controlled in a push-pull manner, each pump is pre-loaded a given amount thereby placing an additional load on its mill motor. Accordingly, changes in apportionment of applied torque to the driven rolls results from increasing the load on one pump and decreasing the load on the other pump by operation of the control valves in accordance with the requirements of the error signal. In this way, torque output of the motors is affected by a momentary rise in angular velocity of one shaft and a momentary fall in angular velocity of the other shaft to maintain the small work roll at its given position in the roll pass.

A modification of my invention is a method of rolling the metal strip or sheet on the rolling mills shown and described herein whereby a mill operator observes the shape of the strip as it issues from the mill and then based upon his observation, controls the amount of deflection in the small diameter work roll to obtain a desired shape in the strip (provided of course that the shape is different from that desired). To control this amount of deflection in the small work roll, the operator increases and decreases the amount of the deflection through effecting changes in apportionment of the torque applied by the motors to the driven upper and driven lower rolls. Such changes in apportionment of the torque comprise increasing and/or decreasing the amount of output torque of the motor or motors which rotate one driven roll relative to the amount of output torque of the motor or motors which turn the other driven roll through operation of controls for the motors.

Such controls are those which govern operation of the motors to effect changes in the proportionment of torque and to control output torque and may include a rheostat or rheostats electrically and operatively connected to the motor or motors driving the upper intermediate roll or the upper backing roll and connected to the motor or motors which drive the lower intermediate roll or the lower backing roll as the case may be. These rheostats are electrically connected in the field circuit of a rotating booster excited from a separate D.C. source such as the booster 190 of FIGURE 16 which is inserted between the neutral points 91 and 92 of the four-motor drive of that figure. A simple manual control is satisfactory, provides a push-pull mode of operation and may comprise a two-plate rheostat mechanically connected together for equal angular rotation with each rheostat electrically connected to its respective field. The connections are such that while one field is increasing in strength the other field is decreasing in strength. The fields have opposing magnetic polarity.

Alternatively, a biasing potentiometer or other suitable controls can be electrically connected to the systems of FIGURES 16, 17 or 19 or to other reversible silicon-controlled rectifier systems which achieve necessary changes in amounts of apportionment of torque applied by the motors to the driven rolls. The foregoing provide an open loop control as distinguished from a closed loop regulating system which has at least one feedback loop.

The systems of FIGURES 16, 17 or 19 are also compatible for use with an automatic strip shape sensor feedback which, of course, results in a closed loop regulating system.

Another example of satisfactory electrical circuitry and arrangement for practicing this modification comprises two motors each driving one roll and connected in parallel electrically from a single generator. Mechanically joined to a rearwardly extension of the shaft of each motor is a smaller drag generator. The two drag generators are electrically connected in a separate power loop through a rotating booster or a reversible silicon-controlled rectifier system which (booster or rectifier system) have in circuit a control which governs current flow and direction through the drag generators, one acting as motor, the other as a generator to add torque output to or subtract same from its respective motor and thereby effect the changes in amounts of output torque of the two motors.

When the mill is stalled, both drag generators act as motors with their output torque proportional to the armature current flowing through the power flow due to the booster (whose field is at a constant strength). One drag generator tends to rotate in the same direction as its motor thereby adding its torque to that of its motor and the other drag generator tends to rotate in the opposite direction to its motor thus subtracting its torque from the torque of its motor.

In rolling metal and with current flow in the loop in the same direction, the drag generator whose torque op-

poses its motor torque rotates in a direction opposite to its motor and becomes a generator with the same armature polarity. At the same time the other drag generator rotates in the same direction as its motor to add its torque to the motor's torque. The armature counter voltage of the other drag generator opposes the booster voltage which is overcome by the voltage of the other drag generator so that the booster supplies the losses of the drag generator. Regarding size and capacity of the drag generators relative to the motors, to obtain a two to one torque apportionment wherein the output torque of one motor is twice that of the other motor requires a drag generator with $\frac{1}{3}$ the horsepower rating of its motor.

The dynamometers 254 and 255 of FIGURE 21 as well as the hydraulic load devices and other comparable components which effect increases and decreases in the output torque of the motor or motors connected to one driven roll relative to the output torque of the motor or motors of the other driven roll can be employed by the mill operator for governing the amount of deflection in the small diameter work roll. Again the operator uses a control connected to the dynamometers, hydraulic load devices and other comparable components to achieve an increase or decrease in output torque imparted to one driven roll relative to the output torque applied to the other driven roll.

The changes in apportionment of the torque for controlling the amount of deflection of the small work roll includes an increase in amount of torque applied to one driven roll or a decrease in amount of torque applied to one driven roll or an increase in amount of torque applied to one driven roll accompanied by a decrease in amount of torque applied to the other driven roll. Regarding this last mentioned change in apportionment of torque, preferably the amount of increase applied to one driven roll is substantially equal to the amount of decrease applied to the other driven roll resulting in a push-pull mode of operation.

This modification of my invention also includes biasing the rotating booster or the reversible silicon-controlled rectifier system or other suitable electrical device to provide a difference in amount of output torques of the two motors. This difference in amount of output torques in turn produces a force differential on one of the two sides of the small work roll (entry side or exit side) and thereby effects a given amount of deflection in the small work roll at the start of rolling. Thereafter, this given amount of deflection is increased or decreased to achieve a desired shape in the strip rolled.

The adjustments of amounts of deflection of the small work roll as well as the given amount of deflection imparted thereto at the outset of rolling can be either in the direction of strip travel or opposite thereto, i.e., towards the entry side or towards the exit side of the mill.

In this modification, sensing of the deflection of the small work roll can be eliminated whereby the operator relies upon his observation of the shape of the strip issuing from the mill and adjusts his controls in accordance with his observation to increase and/or decrease the amount of torque delivered to one or both driven rolls and thereby govern the amount of deflection of the small work roll. For example, increasing the amount of deflection tends to correct buckles or over-rolled parts in the center portion of the strip while decreasing the amount of deflection tends to overcome ripples, wavy edges or buckles along the edges of the strip. Of course, elimination of sensing the deflection of the small work roll permits simplification of electric circuitry including that part which generates the error signal and utilizes same for regulation of the motors connected to the driven rolls.

However, in some instances to assist the roller and indicate to him a position of the small work roll as to the amount of deflection thereof, sensing deflection of the small roll is made by the apparatus shown and described herein. The amount of deflection sensed is then indicated

or shown by a roll position indicator such as indicator 77 which is located for viewing by the operator. Thus, the operator can govern the amount of deflection of the small work roll through the changes in torque apportionment by reliance upon the amount of deflection shown by the indicator and by observation of the shape of the strip being rolled.

In addition to the method which comprises observing the shape of the strip and then based upon the observation, controlling the amount of deflection of the small diameter work roll to obtain a desired shape in the strip, there is another method which achieves satisfactory results. Such other method includes determining the flatness of the strip as it issues from the mill and then controlling the deflection of the small work roll to obtain the desired shape. Determining this flatness may be effected by a sensor or device which detects flatness of the strip widthwise; namely, from lateral edge to lateral edge. One such sensor detects tension stress distribution as related to flatness of the strip widthwise thereof. Such sensor ascertains which portions, if any, of the width of the strip lack flatness and then generates a signal which is related to the portion lacking in flatness and preferably also which is related to the amount of lack of flatness. Then this signal is transmitted to the control which governs operation of the motors to effect changes in the apportionment of torque and thereby regulate the amount of deflection of the small work roll to obtain the desired flatness in the strip. More specifically, the signal is delivered to a booster generator such as 190 of the regulating system of FIGURE 16 through first and second control amplifiers connected to the two push-pull fields of the booster generator. Of course, the regulating systems of FIGURES 17 and 19 can be used as well as the dynamometers of FIGURE 21 and the hydraulic load devices and comparable components which achieve increases and decreases in output torque of the motor or motors connected to one driven roll relative to the output torque of the motor or motors connected to the other driven roll.

Another way of determining flatness of the strip comprises the operator hitting or striking portions of the width of the strip with a stick to ascertain which portion or portions of the width are loose and which are tight. Those portions which are loose or looser than other portions lack flatness and the operator thereupon makes changes in apportionment of torque to the driven rolls of the mill to achieve uniform flatness of the strip and thereby produce flatness or a given shape in the strip.

The size of the small work roll is such as to have adequate stiffness for setting and maintaining given amounts of deflection therein and yet such as to have sufficient flexibility to permit production of changes in amounts of deflection through control of amounts of output torque of the motors for obtaining the desired shape of strip. For example, I have found that 1½ inch diameter small work roll in a 10-inch wide mill is satisfactory and the diameter of the small work roll in larger mills may range up to 8 inches-10 inches for 40-inch-54-inch wide mills.

My invention has important advantages which include:

(a) Ability to utilize a single small diameter work roll for rolling extremely thin gauge strip and sheet such as 0.001" to 0.008" in wide widths up to 50" and above while producing excellent flatness in the metal.

(b) Ability to maintain the single small diameter work roll in a given position in the roll pass and/or to purposely maintain the roll at a given position where there is a small amount of deflection therein either in the direction with or opposite to strip travel to obtain a given shape in the rolled metal.

(c) Ability to effect excellent control over the shape of the very thin strip and sheet through extremely fast correction and compensation for deflection away from the roll's given position where the deflection is caused by transient

conditions such as hard spots or areas, small off-gauge areas, etc., and/or from a deviation from equilibrium conditions between the forward and back tensions and that angular component of force of the roll pressure which tends to force the roll out of its given position.

(d) Ability to make use of tungsten carbide work rolls.

(e) Ability to control position of the single small work roll in the roll pass so as to compensate for heat build-up or crown while producing a high degree of flatness in extremely thin gauges.

(f) Ability to produce desired shape of very thin strip and sheet by observing the shape of the strip issuing from the mill and controlling the amount of deflection of the single small work roll.

While I have shown and described preferred embodiments of my invention, it may be otherwise embodied within the scope of the appended claims.

I claim:

1. In a method of rolling metal sheet or strip on a rolling mill having a small diameter work roll, at least one upper and at least one lower backing roll for said work roll, each of said backing rolls having a diameter greater than said work roll, said rolls being disposed substantially vertically of one another, said work roll and one of said upper and lower backing rolls forming a roll pass through which metal is reduced in thickness, and another of said backing rolls being in frictional engagement with said work roll; said work roll being subjected to deflection in a direction substantially with and substantially opposite to travel of metal through said mill, the invention comprising driving an upper backing roll by at least a first motor operatively connected thereto, driving a lower backing roll by at least a second motor operatively connected thereto, controlling amount of said deflection of said work roll in said roll pass by effecting changes in apportionment of applied torque by said motors between said driven rolls through sensing amount and direction of deflection of said work roll from a given position, from said sensing generating a signal related to amount and direction of deflection, producing from said signal an error signal related to the difference between the sensed position of said work roll and the given position of said work roll and related to the direction of said deflection, utilizing said error signal for increasing and decreasing output torque of one of said motors connected to one driven roll relative to output torque of said other motor connected to said other driven roll for effecting said changes in apportionment of applied torque to said driven rolls to control deflection of said work roll.

2. The invention of claim 1 characterized by said sensing of deflection of said work roll including sensing rate of change of deflection, by said signal being related to rate of change of deflection, and by said error signal being related to a rate of change of amount of difference between said sensed position and said given position of said work roll.

3. The invention of claim 1 characterized by effecting said changes in apportionment of applied torque without substantially affecting the amount of total torque delivered to said driven rolls.

4. In a method of rolling metal sheet or strip on a rolling mill having a small diameter work roll, at least one upper and at least one lower backing roll for said work roll, each of said backing rolls having a diameter greater than said work roll, said rolls being disposed substantially vertically of one another, said work roll and one of said upper and lower backing rolls forming a roll pass through which metal is reduced in thickness, and another of said backing rolls being in frictional engagement with said work roll, said work roll being subject to deflection in a direction substantially with and substantially opposite to travel of metal through said mill, the invention comprising driving an upper backing roll by at least a first electric motor operatively connected thereto, driving a lower backing roll by at least a second electric

motor operatively connected thereto, controlling amount of said deflection of said work roll in said roll pass by effecting changes in apportionment of applied torque by said motors between said driven rolls through sensing amount and direction of deflection of said work roll from a given position, from said sensing generating a signal related to amount and direction of deflection, producing from said signal an error signal related to the difference between the sensed position of said work roll and the given position of said work roll and related to the direction of said deflection, producing from said error signal a current related to the magnitude of said error signal and related to the direction of said error signal, applying said current to said motors for effecting changes in apportionment of applied torque to said driven rolls by increasing and decreasing said torque applied to one driven roll relative to the torque applied to said other driven roll to control deflection of said work roll.

5. The invention of claim 4 characterized by said sensing of deflection of said work roll including sensing rate of change of deflection by said signal being related to rate of change of deflection, by said error signal being related to a rate of change of amount of difference between said sensed position and said given position of said work roll, and characterized by said current being related to the rate of change of said error signal.

6. The invention of claim 4 characterized by effecting said changes in apportionment of applied torque without substantially affecting the amount of total torque delivered to said driven rolls.

7. The invention of claim 4 characterized by applying said current to the armatures of said motors.

8. The invention of claim 4 characterized by so producing said current that it comprises a first part which is substantially continuous, is related in magnitude and related to the direction of said deflection, and comprises a second part which is pulses of short duration related in magnitude and related to the direction of said deflection, said first part being a major portion of said current and requiring a longer time interval to effect a change in said apportionment of applied torque than said second part.

9. The invention of claim 5 characterized by so producing said current that it comprises a first part which is substantially continuous, is related in magnitude and related to the direction of said deflection, and comprises a second part which is pulses of short duration related in magnitude and related to the direction of said deflection, said first part being a major portion of said current and requiring a longer time interval to effect a change in said apportionment of applied torque than said second part, at least one of said first and second parts of said current being related to rate of change of said deflection of said work roll.

10. In apparatus for controlling deflection of a small diameter work roll of a mill for rolling metal in a roll pass of said mill, said deflection being in a direction with and opposite to travel of metal through said mill, said mill having at least one upper and at least one lower backing roll for said work roll, each of said backing rolls having a diameter greater than said work roll, said rolls being disposed substantially vertically of one another, said work roll and one of said upper and lower backing rolls forming said roll pass through which metal is reduced in thickness and another of said backing rolls being in frictional engagement with said work roll, the invention comprising:

- (a) at least a first motor drivingly connected to an upper backing roll,
- (b) at least a second motor drivingly connected to a lower backing roll,
- (c) means for sensing amount and direction of said deflection of said work roll, said sensing means being opposite a face of said roll so that deflection is toward and away therefrom,

- (d) signal generating means connected to said sensing means for producing from said deflection a signal related to amount of deflection and related to direction of said deflection,
- (e) error signal generating means connected to said signal generating means for producing from said signal an error signal related to the difference between a sensed position of deflection of said work roll and a given position of said work roll and related to the direction of said deflection,
- (f) error signal transmitting means connected to said error signal generating means and connected to one of said motors and of means coupled to said motors for increasing and decreasing output torque of said motors to said driven rolls to effect changes in apportionment of applied torque to said driven rolls to control deflection of said work roll.

11. The invention of claim 10 characterized by said signal generating means being such that said signal is related to rate of change of deflection of said work roll, and by said error signal generating means being such that said error signal is related to rate of change of deflection of said work roll.

12. In apparatus for controlling deflection of a small diameter work roll of a mill for rolling metal in a roll pass of said mill, said deflection being in a direction with and opposite to travel of metal through said mill, said mill having at least one upper and at least one lower backing roll for said work roll, each of said backing rolls having a diameter greater than said work roll, said rolls being disposed substantially vertically of one another, said work roll and one of said upper and lower backing rolls forming said roll pass through which metal is reduced in thickness and another of said backing rolls being in frictional engagement with said work roll, the invention comprising:

- (a) at least a first motor drivingly connected to an upper backing roll,
- (b) at least a second motor drivingly connected to a lower backing roll,
- (c) means for sensing amount and direction of said deflection of said work roll, said sensing means being opposite a face of said roll so that deflection is toward and away therefrom,
- (d) signal generating means connected to said sensing means for producing from said deflection a signal related to amount of deflection and related to direction of said deflection,
- (e) error signal generating means connected to said signal generating means for producing from said signal an error signal related to the difference between a sensed position of deflection of said work roll and a given position of said work roll and related to the direction of said deflection,
- (f) controllable variable load producing means coupled to said motors for increasing and decreasing output torque of said motors to said driven rolls, being connected to said error signal generating means and being responsive to said error signal to effect changes in apportionment of applied torque to said driven rolls to control deflection of said work roll.

13. The invention of claim 12 characterized by said signal generating means being such that said signal is related to rate of change of deflection of said work roll and by said error signal generating means being such that said error signal is related to rate of change of deflection of said work roll.

14. In apparatus for controlling deflection of a small diameter work roll of a mill for rolling metal in a roll pass of said mill, said deflection being in a direction with and opposite to travel of metal through said mill, said mill having at least one upper and at least one lower backing roll for said work roll, each of said backing rolls having a diameter greater than said work roll, said rolls being disposed substantially vertically of one another, said

work roll and one of said upper and lower backing rolls forming said roll pass through which metal is reduced in thickness and another of said backing rolls being in frictional engagement with said work roll, the invention comprising:

- (a) at least a first electric motor operatively connected to an upper backing roll,
- (b) at least a second electric motor operatively connected to a lower backing roll,
- (c) means for sensing amount and direction of said deflection of said work roll, said sensing means being opposite a face of said roll so that deflection is toward and away therefrom,
- (d) signal generating means connected to said sensing means for producing from said deflection a signal related to amount of deflection and related to direction of said deflection,
- (e) error signal generating means connected to said signal generating means for producing from said signal an error signal related to the difference between a sensed position of deflection of said work roll and a given position of said work roll and related to the direction of said deflection,
- (f) means connected to said error signal generating means for producing from said error signal a current related to the magnitude of said error signal and related to the direction of said error signal, said current producing means being connected to said motors for regulating operation thereof to effect changes in apportionment of applied torque to said driven rolls by increasing and decreasing said torque to control deflection of said work roll.

15. The invention of claim 14 characterized by said signal generating means being such that said signal is related to rate of change of deflection of said work roll, by said error signal generating means being such that said error signal is related to rate of change of deflection of said work roll, and by said current producing means being such that said current is related to the rate of change of said error signal.

16. The invention of claim 14 characterized by said current producing means being connected to the armatures of said motors.

17. The invention of claim 14 characterized by a first pair of electric motors at least one of which is drivingly connected to said upper backing roll, a second pair of electric motors at least one of which is drivingly connected to said lower backing roll, an armature of one of said first pair motors connected electrically in series with an armature of one of said second pair motors to form a first neutral point between said series connection, an armature of the other of said first pair motors connected electrically in series with an armature of the other of said second pair motors in the opposite direction to form a second neutral point between said series connection, a neutral circuit between said first and second neutral points, said armature of said one of said first pair motors and said armature of said other of said second pair motors being connected to one side of a generator which drives all said motors, said armature of said other of said first pair motors and said armature of said one of said second pair motors being connected to the other side of said generator, said current producing means being connected into said neutral circuit and being such that current produced thereby increases the armature current in one of the two pairs of motors and decreases the armature current in the other of the two pairs of motors.

18. The invention of claim 17 characterized by said current producing means including a first operative means which produces a substantially continuous current and a second operative means which produces pulses of current of short duration.

19. The invention of claim 17 characterized by said current producing means being a rotating booster with fields connected in push-pull relationship and being two

silicon controlled rectifiers each of which is in electrical connection with a rectifier bridge whose output is applied to said neutral circuit, said rotating booster producing a substantially continuous current and said silicon controlled rectifiers producing pulses of current of short duration.

20. The invention of claim 17 characterized by said current producing means being an adjustable voltage, reversing polarity regulator formed by a pair of rectifier bridges including back-to-back connected silicon controlled rectifiers, said rectifier bridges being resistor coupled, said reversing polarity regulator being connected into said neutral circuit.

21. In a method of rolling metal sheet or strip on a rolling mill having a small diameter work roll, at least one upper and at least one lower backing roll for said work roll, each of said backing rolls having a diameter greater than said work roll, said work and backing rolls being disposed substantially vertically of one another, said work roll and one of said upper and lower backing rolls forming a roll pass through which metal is reduced in thickness, and another of said backing rolls being in frictional engagement with said work roll, said work roll being subject to deflection in a direction substantially with and substantially opposite to travel of metal through said mill, the invention comprising driving an upper backing roll by at least a first motor operatively connected thereto, driving a lower backing roll by at least a second motor operatively connected thereto, determining shape of the strip issuing from said mill, from said determination controlling the amount of said deflection of said work roll in said roll pass so as to obtain a given shape in said strip by effecting changes in apportionment of torque applied by said motors to said driven rolls, said effecting being made by increasing and decreasing output torque of one of said motors connected to one driven roll relative to output torque of said other motor connected to said other driven roll through operation of controls for said motors.

22. The invention of claim 21 wherein the output torque of said one motor is increased an amount substantially equal to the amount the output torque of said other motor is decreased.

23. The invention of claim 21 characterized by sensing amount of said deflection of said work roll, showing said sensed amount of deflection, utilizing at least one of said determining and of said sensing and showing of said sensed amount of deflection in controlling the amount of deflection of said work roll to obtain a given shape in said strip.

24. In a method of rolling metal sheet or strip on a rolling mill having a small diameter work roll, at least one upper and at least one lower backing roll for said work roll, each of said backing rolls having a diameter greater than said work roll, said work and backing rolls being disposed substantially vertically of one another, said work roll and one of said upper and lower backing rolls

forming a roll pass through which metal is reduced in thickness, and another of said backing rolls being in frictional engagement with said work roll, said work roll being subject to deflection in a direction substantially with and substantially opposite to travel of metal through said mill, the invention comprising driving an upper backing roll by at least a first motor operatively connected thereto, driving a lower backing roll by at least a second motor operatively connected thereto, sensing amount of deflection of said work roll, showing said sensed amount of deflection, utilizing said sensed amount of deflection in controlling the amount of said deflection of said work roll in said roll pass so as to obtain a given shape in said strip by effecting changes in apportionment of torque applied by said motors to said driven rolls, said effecting being made by increasing and decreasing output torque of one of said motors connected to one of said driven rolls relative to output torque of said other motor connected to said other driven roll through operation of controls for said motors.

25. In a method of rolling metal sheet or strip on a rolling mill having a small diameter work roll, at least one upper and at least one lower backing roll for said work roll, each of said backing rolls having a diameter greater than said work roll, said rolls being disposed substantially vertically of one another, said work roll and one of said upper and lower backing rolls forming a roll pass through which metal is reduced in thickness, and another of said backing rolls being in frictional engagement with said work roll, said work roll being subject to deflection in a direction substantially with and substantially opposite to travel of metal through said mill, the invention comprising driving an upper backing roll by at least a first motor operatively connected thereto, driving a lower backing roll by at least a second motor operatively connected thereto, determining amount of said deflection of said work roll in said roll pass by effecting changes in apportionment of applied torque by said motors between said driven rolls.

26. The invention of claim 21 wherein said determination is made by visual observation of the shape of the strip issuing from the mill.

27. The invention of claim 21 wherein said determination is made by sensing the flatness of the strip issuing from the mill.
